UNITED STATES PATENT OFFICE.

WARNER R. BUXTON, OF LONGMEADOW, MASSACHUSETTS.

CASE FOR KEYS AND THE LIKE.

Application filed February 8, 1923. Serial No. 617,788.

This invention relates to improvements in cases for keys or the like and is a further development of the invention disclosed in United States Letters Patent No. 1,261,692, granted to me on April 2, 1918.

According to this patent, the key retaining members are arranged in a single group and, in practice, this single group of members would naturally be used to retain all sorts of keys, including perhaps keys which are used only infrequently as well as keys which may be used many times during a single day. When one carries a large number of keys, it is manifest that, with the arrangement described, the selection of keys of either class is hampered by the presence of keys of the other class in the same group.

The general object of this invention is the segregation of the key retaining members into a plurality of groups to enable the user to classify his keys on the basis of the frequency with which they are used or on any other basis, according to the wishes and desires of the user.

More particularly, it is an object of the invention to provide in a key case a number of key retaining members of a construction such as to enable the user to arrange them into a plurality of groups or to locate one or more of them in various locations in the key case to suit his own convenience.

Another object of the invention is to provide in a key case having a plurality of groups of key retaining members, means for normally holding each group of members and their keys from movement out of the case, said means arranged so that either group of members can be released for movement into and out of the case without releasing the other group.

Another object of the invention is to provide, in a key case, improved key retaining members each of which is provided with an individual support adapted for attachment to the case,—characterized in that the key holders may be variously located in the case, as desired, and spaced and grouped in various ways to suit the pleasure of the user.

Another object of the invention is to provide an improved individual support for a key retaining member, consisting of a one piece metal stamping, provided with bearing means for pivotally supporting a single key retaining member and other means for attaching it to the key case.

A further object of the invention is to pro-

vide a support, of the general character just alluded to, which is provided with improved bearing means to support the key retaining member for both pivotal and swivelling movement.

Other objects and advantages will appear in the following description and in the illustrative embodiment of the invention in the accompanying drawings, in which

Figs. 1 and 2 are top plan and front elevational views respectively of one form of key case embodying my invention;

Fig. 3 is an elevational view thereof showing both sections of the case in open position;

Figs. 4 and 5 are elevational and bottom plan views, respectively, of the key case showing one section only in open position;

Fig. 6 is a front elevational view of another type of key case embodying my invention,—the case being shown as open to expose one of the two groups of key retaining members;

Fig. 7 is a similar view showing the case open to expose the other group of key retaining members;

Fig. 8 is a bottom plan view of Fig. 7;

Fig. 9 is a sectional view taken on the line 9—9 of Fig. 7;

Fig. 10 is a vertical sectional view of a third type of key case embodying the invention;

Fig. 11 is a side elevational view of a closed key case like that shown in Figs. 2 or 10 illustrating the shape assumed by the case after it has been in use for some time;

Figs. 12 and 13 are plan views illustrative of two successive steps in the manufacture of one of the individual supports for the key retaining members;

Fig. 14 is an end elevational view showing a third step in the manufacture of the support;

Fig. 15 is a perspective view of the completed support; and

Figs. 16 and 17 are fragmentary cross-sectional and front elevational views, respectively, showing the mounting of the supports in the key case and the mounting of the key retaining members in their supports.

Referring to these drawings; the case forming member of the key case may, according to the broader features of the invention, be variously constructed, as desired. Several different case constructions have

been illustrated as examples and various other examples will readily occur to those skilled in the art. Likewise the key retaining members, which usually take the form of snap hooks, such as those indicated by *h*, may be variously constructed, as desired. The broader concepts of the invention are largely independent of structural details and relate more particularly to the segregation of the key retaining members into a plurality of groups. Thus, as shown in Figs. 3, 6, and 10, there are two groups of key retaining members A and B and either group may be restrained, or rendered accessible, independently of the other group by various means, which will hereinafter be described in full detail.

While this feature of segregating the key retaining members into two or more groups does not necessarily depend on the use of any particular style of support for the key retaining members and the invention can be practised to a certain extent with various types of supports, heretofore used in ordinary key cases, yet greater freedom for the segregation is allowed by the use of an individual support for each key retaining member. By so doing, one can control the number of units in a group according to his own particular will and pleasure and, if these individual supports are so constructed as to be readily attached to, or detached from, the case by the user, as illustrated, the supports may be placed at any desired locations to suit the convenience and particular ideas of the user.

In order to illustrate one suitable example of an individual support of the character just mentioned, reference is made to Figs. 12 to 17, inclusive. The support there shown may be constructed from sheet metal by comparatively simple punch press and binding operations. Thus, a blank of flat, thin metal having a relatively narrow strip 20 with a point or prong 21 at one end thereof, is provided with substantially circular ears 22 which are oppositely located at the other end of the strip. The ears 22 are subjected to a punch press operation to produce concavities 23 therein, the surfaces of which are portions of spherical surfaces. The ears are then bent upwardly toward one another, from the position shown by dotted lines in Fig. 14 to that shown by full lines, and in such a manner that the surfaces of the concavities 23 will coincide substantially with the surface of a common sphere placed between them. The strip 20 is then bent backwardly upon itself, as indicated in Fig. 15, and the prong 21 upturned, as shown. The strip 20, bent as shown in Fig. 15, can be applied to the key case in any desired position, as indicated in Figs. 16 and 17—the strip being eventually bent into substantially U-shaped form and the prong 21 passing

through the case to hold the device in place. The end of this prong 21 may, if desired pass through an opening 24 in the strip 20 and be riveted in place, if a permanent connection is desired.

The concavities 23 form bearing means for a key retaining member, such as the snap hook *h*, and, as shown, are designed to receive an approximately spherical head 25 on the snap hook and permit the latter to swing in a definite arc-like path into and out of the key case as well as swivel in the socket provided by the ears 22. The head 25 is inserted between the ears 22 prior to the bending operation illustrated in Fig. 14. The swivelling movement, while generally desired, is not necessarily essential according to all features of the invention. The hook *h* is recessed, as at 26, just below head 25 to provide a substantially cylindrical portion of suitable width to pass out of the socket in the space between ears 22, which portion can turn about its own axis to permit the swivelling movement. For a full disclosure of one example of a suitable retaining member reference is made to my U. S. Letters Patent No. 1,439,863 granted December 26, 1922.

The individual supports, with their key retaining members, may be applied in many ways and in various locations to any suitable kind of key case of the same general class as that under consideration. There are, however, several types of key cases which are particularly useful for the purpose of segregating the keys into groups and which, as is generally desired, have provisions made for restraining or releasing each group, when desired.

One of these key cases is shown in Figs. 1 to 5 inclusive and will now be described in detail. The case forming member consists of a relatively long strip 30 of suitable material, such as leather or the like, which strip is foldable along the lines 31, 32, 33, and 34, thus dividing the strip into several sections. The central section 35, as at present contemplated, constitutes the supporting section for the key retaining members and groups A and B, of the individual supports described, are applied at the upper and lower portions, respectively, of section 35, so that the key retaining members of one group, as A, lie on the front face of this section and the members of the other group, as B, lie on the back of this section. The section 36 constitutes a flap to overlie and cover the front face of section 35 and is provided with a flap 37, on which is secured a fastener 39, adapted to engage with a fastener 40 on a section 41 to releasably hold the covering flap in closure forming relation with the front face of section 35. The section 41 is adapted to be folded along line 33 rearwardly and backwardly upon the rear

face of section 35 and is provided with a flap 42, which carries a fastener 43, adapted to engage with a fastener 44 on section 36 to releasably hold flap 41 in closure forming relation with the rear face of section 35. The case, in completely closed position, is shown in Fig. 1 and both groups of key retaining members are then restrained from moving out of the case. By detaching the fasteners 39 and 40, flaps 36 and 37 may be swung to the position illustrated in Fig. 4 to expose group A and release the key retaining members thereof for swinging movement into and out of the case. Meanwhile, group B is restrained, as shown in Fig. 5. To release group B, the fasteners 43 and 44 (Fig. 1) are disengaged and flaps 41 and 42 swing outwardly, which of course, can be done without releasing group A.

A second form of case, having more the appearance of the usual key case, is shown in Figures 6 to 9, inclusive. This case consists of a strip 45 having a central section 46 and foldable flaps 47 and 48 on opposite sides thereof. Interengageable fasteners 49 and 50 are provided on the flaps and these flaps are ordinarily releasably held together in overlapping relation over the front face of section 46 by the fasteners in the usual manner. The flaps may, however, be folded rearwardly in overlapping relation over the rear face of section 46 and releasably held in this relation by the same fasteners, which arrangement is illustrated in Figs. 8 and 9 and is utilized for a purpose later to be described. Overlying the front face of section 46 is a flap 51 which is secured thereto at its upper edge in a manner such as to permit it to be swung upwardly and then rearwardly into overlying relation with the rear face of section 46, as shown in Fig. 8, the flap 51 being releasably held in this position by the rearwardly folded flaps 47 and 48. Mounted on flap 51 near its upper and hinged end is a group A of key retaining members. When flap 51 is swung rearwardly as described, this group of key retaining members is carried with the flap and held between it and the rear face of section 46, as best shown in Fig. 9. The key case in Figs. 7 and 9 is shown inverted from the position shown in Fig. 6, for the purpose of bringing the second group B of key retaining members into operative position. The members of group B are designed for keys which are used only infrequently and they are normally covered by flap 51 as shown in Fig. 6. The supports for the members of group B are secured to the bottom of section 46 and the flap 51 is normally fastened to the base of this section by fasteners 52 to hold the retaining members of group B, and the keys thereon, against movement out of the case. This type of key case, as far as its outward appearance goes, is like the ordinary

key case and is operated exactly in the same way, as far as the members of group A are concerned. When, however, a key from group B is desired, the flap 51 is raised, turned backwardly and fastened by flaps 49 and 50 and inverted all as shown in Fig. 9.

A third form of key case is shown in Fig. 10 and this article is really a double key case made up of two standard key cases, like those disclosed in my first named patent, which have their backs 55 and 56 sewed together in inverted relation bringing the two groups of key retaining members at opposite ends of the case.

With all three styles of key cases described, it is an advantageous feature to have the two groups of key retaining members at opposite ends of the case. The reason for this arrangement will best appear from Fig. 11, which may be assumed to be a case like that shown in Fig. 10 and one which has been loaded with keys and used for some time. An ordinary single key case tends to bulge at a point about one third way down from the end at which the key retaining members are located. This bulge is indicated at 57. The case, under such conditions, is thicker at one end than at the other and converges, with relation to the back, from the bulge to that end of the case remote from the key holders. By mounting the two cases back to back in inverted relation, the bulging of one, near the top, is offset by the bulging of the other near the bottom and, although the covering flaps 58 of each converge with relation to their backs 55 and 56, they are approximately parallel with each other and a case more uniform in thickness from end to end is provided.

Although the key retaining members have been shown in two oppositely located groups, as is generally desired, the individual support for each member is so constructed that groups or individual key retaining members may be otherwise located as may be desirable. These supports are adapted for attachment to the case at any convenient point and may be placed on the back of the case or on the flaps thereof, as desired.

The invention is broadly characterized by the provision of means which allow each user wide latitude in arranging the retaining members to suit his own purposes and fancy. The invention admits of flexibility in disposing the retaining members and offers unlimited opportunity for the user to express his individual ideas as to how a key case should be arranged.

The invention has been disclosed herein, in an embodiment at present preferred with detailed variations, for the purposes of illustration but the scope of the invention is defined by the appended claims rather than by the foregoing description.

I claim:

1. In a key case, a housing for a plurality of groups of key retaining members, said housing having a partition therein, said partition supporting one of said groups of key retaining members, one portion of said housing serving to restrain from movement and release for movement one group of said key retaining members, and another portion of said housing serving to restrain from movement and release for movement another group of said retaining elements.

2. A key case comprising, case forming means affording a back and side flaps foldable over the back together with a flap connected to the back along a line transverse to the lines of fold of the first named flaps, and adapted normally to lie adjacent one side of said back and to be enclosed by the first named flaps when the same are folded over the back, a group of key retaining members mounted on the back for swinging movement and normally concealed beneath and restrained from movement out of the case by the last named flap, and a group of key retaining members mounted on the last named flap and normally restrained from movement out of the case by said first named flaps when the same are folded over the

back, the last named flap being movable to lie on the opposite side of said back and when so moved carrying the last named group of key retaining members therewith and holding the same between it and the back, thereby exposing the first named group of key retaining members and releasing them for movement into and out of the case.

3. The combination in a key case, of a back, a group of key retaining members mounted near one end and disposed on one face of said back, a second group of key retaining members mounted near the other end and disposed on the opposite face of said back, and foldable flaps for enclosing each of said groups.

4. In a key case a housing, a plurality of key retaining means mounted thereon, said housing comprising a plurality of foldable sections one of which serves to restrain from movement and release for movement a portion of said key retaining means and another of which serves to restrain from movement and release for movement the remainder of the key retaining means.

In testimony whereof I have affixed my signature.

WARNER R. BUXTON.
